WEATHER STRIP

Philip R. Oftedal, Chicago, Ill.

Application June 24, 1932. Serial No. 619,056

2 Claims. (Cl. 20—69)

My invention relates to improvements in metal weatherstrips for windows and has as one of its objects the production of a weatherstrip having wide limits of adjustment adapting it to fit and compensate for substantial variations in the space between the sash and the window frame.

More particularly the invention contemplates a weatherstrip of the kind described having interlocking members equally adapted to cooperate 10 and shut out the weather both when the window sash are swollen by reason of damp weather and are shrunk during dry weather.

A further object of the invention is the provision of a two piece weatherstrip adapted to be 15 economically constructed from sheet metal or the like and for installation on windows having sliding sashes, one of said pieces being fastened to the window frame and the other being fastened to the sash without requiring any alteration of 20 the frame and slight or no alteration of the sash.

Still another object of the invention is the provision of a weatherstrip which is simple, durable, economical and satisfactory for its intended purpose.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawing, wherein like reference characters indicate like or corresponding parts,

Fig. 1 is a fragmentary view through a window showing both the upper and the lower sash equipped with one embodiment of the invention; and

Figs. 2 and 3 are perspective views of the strips comprising the device.

Referring now more particularly to the drawing, the numeral 10 illustrates the jamb of a conventional window frame or casing providing a sash groove or space 11 between a molding 13 and a parting strip 14 and a groove or space 12 between the parting strip 14 and a molding 15. Upper and lower sash 16 and 17 are respectively vertically movable in the grooves 11 and 12.

The weatherstrips each comprise cooperating members 20 and 30, the members 20 being mounted on and movable with each of the sash 16 and 17 and the members 30 being fixedly mounted on the frame 10. The member 20 interlocks with the member 30 to form a weatherstrip which is

self adjusting to provide air and weathertight closures for the variable width spaces 11 and 12 between the frame 10 and the edges 18 and 19 of the sash 16 and 17 respectively. The size of the spaces 11 and 12 vary according to the swelling or shrinking of the sash and the window frame in wet and dry weather. The interlocking construction of the weatherstrips also adapts a window or frame of a standard or given dimension as a satisfactory mounting for sash of slightly different widths and avoids the necessity of providing sash of exact dimensions since the weatherstrip members interlock in a manner to permit substantial lateral shifting of the sash relative to the frame 10.

The members 20 and 30 possess sufficient flexibility and interlock in such a manner that they hold the sash snugly against the molding 15 to eliminate rattling of sash in windy weather, there being otherwise more or less side movement of the sash in the runway provided for moving the sash up and down.

The edges of the sash 16 and 17 are provided with recesses 39 adjacent the parting strip 14, such recesses being of a depth sufficient to contain the interlocking portions of the members 20 and 30. The members 30 preferably extend the full height of the frame 10 on which they are fixedly mounted and the members 20 extend substantially the full length of the sash.

The middle portion of the member 20 is folded to provide a loop 25 extending substantially the full depth of and in contact with one wall of the recess 39. One edge portion of the member 20 forms a flange 21 extending at substantially right angles to the loop 25 with its marginal edge 22 turned and folded along the flange. The intermediate portion of the flange 21 provides a corrugation 23 and is fastened to the edge of the sash by nails or tacks 24. The corrugations 23 are of sufficient depth that the heads of the nails 24 positioned therein clear the frame 10 as the sash are moved up and down in opening and closing the window.

The edge portion 27 of the member 20, opposite to the flange 21, is turned back in substantially parallel spaced apart relation to the loop 25 with its marginal edge portion turned to provide a rim 28. The loop 25 provides a bead 26 along its line of bend, the bead contributing flexibility and permitting the loop to open up and close without undue strain on the material and also provides a contact point cooperating with the adjacent portion of the member 30 when the members are assembled in interlocking rela-

tion. The line of fold between the loop 25 and the edge portion 27 provides a bead 29 permitting lateral yielding of the member 20 without undue strain on the material and so arranged as 5 to contact with the frame member 30 upon movement of the sash towards the frame 10.

A pair of members 30 are positioned on each side jamb of the frame 10 on opposite sides of the parting strip 14. The members 30 are preferably continuous and extend the full depth of 10 the parting strip 14 with their mid-portions folded to provide a double thickness rib 34 extending along and in contact with the frame. The bending line of the rib 34 provides a bead 35 with 15 which the flange 21 of the member 20 contacts when the sash is moved towards the frame. The strip 14 is partially embedded in and closely fits a vertically extending groove 40 formed in the side jamb of the frame 10. The edge portion 36 20 of the member 30 on one side of the rib 34 lines the side of the groove 40 and has its marginal edge providing a flange 37 resting upon the bottom of the groove. The extreme marginal edge portion of the flange 37 is folded back to provide 25 a rim 38 to avoid possibility of injury to workmen in handling the members 30 during assembly and construction. The wedging action of the parting strip 14 in the groove 40 securely fastens the members 30 to the frame 10.

30 The portion of the member 30 opposite to the flange 36 is folded to provide a U-shaped member 31 having its extreme marginal edge turned inwardly to form a bead 33. In assembling the members 20 and 30, the edge portion 27 of the 35 member 20 is positioned in and interlocks with the loop 31 of the member 30. In their assembled interlocking position the fixed frame member 30 thereby provides a runway for the movable sash member 20.

40 In opening and closing the window there is a well known tendency for the sash to move towards and away from the frame 10 and the described construction and interlocking of the members 20 and 30 limits the amount of lateral movement of the sash relative to the frame. In case 45 of lateral movement of the sash away from the frame, the bead 25 comes into contact with the bead 33 providing a stop limiting the amount of such movement and also effectively sealing the 50 space between the members against the passage of air or moisture. If the sash is moved towards the frame in opening or closing, the bead 29 contacts with the bead 35 thereby sealing the space between the frame and the sash against the passage 55 of air and moisture.

Intermediate the described extreme inward and outward positions of the sash relative to the frame 10, the interlocking members 20 and 21, constructed and assembled as described, provide a narrow restricted tortuous passage way preventing flow of air therethrough and effectively sealing the spaces by reason of the contact of the beads of one member with the adjacent portions of the other member. The beads 26 and 29 on the member 20 and the bead 32 on the member 30 not only tend to restrict the clear spaces between the cooperating portions of the members

20 and 30 but also provide lines of bend permitting the members to yield transversely without unduly straining the material in the event of pressure exerted sidewise upon the window. The beaded portions provide sufficient rigidity to prevent substantial side movement of the sash and thereby avoid contact of the sash in raising and lowering and also provides sufficient resistance to wind pressure to avoid rattling of the sash both when 80 opened and closed.

Having thus described my invention what I claim as new and desire to secure by Letters Patent is:

1. A weatherstrip of the kind described comprising two cooperating members one adapted to be mounted on and movable with a sliding sash and the other adapted to be fixedly mounted on a window frame, said movable member having one edge portion comprising a flange adapted to be fastened to the edge of the sash, said flange having its marginal edge inturned and its middle portion corrugated to provide a nailing line, the middle portion of said movable member being folded to provide a loop extending along the side of the sash with the extremity of said loop providing a bead, the other edge portion of the movable member being folded to provide a flange in spaced substantially parallel relation to said loop, said fixed member having one edge portion folded to provide a loop telescoping over said last mentioned flange with its line of fold forming a bead in yieldable sliding contact with the bead on the movable member, the middle portion of said fixed member being folded to provide a narrow rib projecting substantially perpendicular to its looped edge portion, the extremity of said rib providing a bead, the other edge of said fixed member extending substantially perpendicular to said rib and having its marginal edge forming a flange extending oppositely to and substantially parallel 105 with said rib.

2. In combination a window frame having a vertically extending groove in its side, upper and lower sash slidably mounted in the frame and a parting strip partially embedded in said groove with its projecting portion separating said sash, of a weatherstrip comprising two cooperating members closing the space between said frame and sash, one of said members having its middle portion folded to form a rib positioned in said space and extending along the side of the frame with one edge portion wedged between the parting strip and the side and bottom walls of said groove and its other edge portion folded to form a narrow 110 loop extending along the side of the projecting portion of the parting strips, the lines of bend of said loop and rib each forming a bead, the other of said members having one edge providing a corrugated flange fastened to the edge of the sash adjacent said rib with its middle portion folded 115 to provide a loop positioned between the first mentioned loop and the side of the sash with its line of bend forming a bead contacting with the bead on said first mentioned loop and its edge portion opposite said flange extending into the first mentioned loop substantially the full depth thereof.

PHILIP R. OFTEDAL.
